CLAIM

The ornamental design for a combination transcutaneous electrical nerve stimulation device and microcurrent electrical neuromuscular stimulator, as shown and described.

DESCRIPTION

The nature and intended use of the article in which the design is embodied is a transcutaneous electrical nerve stimulation device (TENS) and a microcurrent frequency generating device known as a microcurrent electrical neuromuscular stimulator (MENS) commonly known as a TENS/MENS unit.

FIG. 1 is a top perspective view of the TENS/MENS unit, showing my new design;

FIG. 2 is a top view thereof;

FIG. 3 is a right side view thereof;

FIG. 4 is a left side view thereof;

FIG. 5 is a front view thereof;

FIG. 6 is a back view thereof; and,

FIG. 7 is a bottom view thereof.
